(57) **CLAIM**

The ornamental design for a display screen with graphical user interface, as shown and described.

DESCRIPTION

FIG. 1 is a front view of a display screen with graphical user interface showing my new design; and,
 FIG. 2 is a front view of the display screen with graphical user interface of FIG. 1 shown on a device.

The broken line showing of the selected alphabetical characters and the remainder of the display screen in FIGS. 1 and 2, and the remainder of the device having the display screen in FIG. 2, is for environmental purposes only and forms no part of the claimed design.
